**HIGHWAY CROSSING PROTECTION
CONTROL APPARATUS**

Ralph R. Kemmerer, Swissvale, and Lucas A. Damasio, Wilkinsburg, Pa., assignors to Westinghouse Air Brake Company, Wilmerding, Pa., a corporation of Pennsylvania

Application August 28, 1953, Serial No. 377,222

9 Claims. (Cl. 246—130)

Our invention relates to highway crossing protection control apparatus, and in particular to apparatus for controlling crossing gates at a highway-railway grade crossing.

At points where railways and highways intersect at grade, it is often desirable to provide highway crossing gates to prevent highway traffic from crossing the intersection when a train is approaching. In the past it has been common practice to provide two sets of gates, one set on each side of the intersection, and when a train enters the track section including the highway crossing, all the gates will become lowered. With all four gates being lowered at the same time, there is a possibility that an automobile traveling along the highway might be trapped between the two sets of gates.

In order to avoid this possibility, some crossings have been provided with only two gates, one on each side to prevent vehicle traffic from entering the intersection but not barring exit from the intersection in the event that the gates should be lowered while a vehicle was on said intersection. Such an arrangement, however, will not prevent pedestrians from attempting to traverse the crossing.

Accordingly, it is an object of our invention to provide highway crossing protection control apparatus which will prevent pedestrians from traversing the crossing when the gates are lowered and will not trap vehicles between the gates in the event that the gates become lowered while a vehicle is on said crossing.

Another object of our invention is to provide apparatus which will cause the traffic gates, that is the gates which obstruct entrance to the crossing, to commence moving to their horizontal position prior to the lowering of the non-traffic gates, that is the gates which obstruct exit from the crossing, so that any traffic which has entered the intersection just prior to a train entering the track section including the intersection will be able to pass through the intersection before the non-traffic gates are lowered to bar the way.

A further object of our invention is to provide apparatus which will cause the non-traffic gates to commence rising prior to the traffic gates so that the highway will be unobstructed when the traffic gates rise to permit highway traffic to enter the crossing.

Still a further object of our invention is to provide apparatus of the type described in which a highway crossing signal will be actuated prior to the traffic gates being lowered so as to warn oncoming traffic of the approaching train.

Yet another object of our invention is to provide circuits which will check the integrity of our highway crossing control apparatus and will actuate the highway crossing signals in case certain circuit elements are not operating properly.

According to our invention we provide slow-pickup relay means which becomes deenergized when a train enters a track section which is intersected by a highway. Upon the release of the slow-pickup relay means, the mechanisms controlling the gates which obstruct entrance

2

to the crossing, that is the traffic gates, become deenergized and the traffic gates commence moving to their horizontal position. When the traffic gate mechanisms become deenergized, a slow-release relay means will become deenergized and, upon the release of this slow-release relay means, the mechanisms which control the gates obstructing exit from the crossing, that is the non-traffic gates, commence moving to their horizontal position.

10 When the train vacates the crossing section the slow-release relay means picks up and the non-traffic gates commence moving to their vertical position. Also upon the train vacating the crossing section, the slow-pickup relay means becomes energized and, when this relay means picks up, the traffic gates commence moving to their vertical position. We further provide circuit means for controlling a highway crossing signal. This circuit means is so arranged that the highway crossing signal becomes energized upon a train occupying the crossing section. We further provide means in the circuit means for controlling the highway crossing signal for checking the operation of the slow-release relay means and, if this is not operating properly, the crossing signal will become energized, so as to warn maintainers that the apparatus is not functioning properly.

Other objects of our invention will appear herein-after as the characteristic features of construction and mode of operation of our invention are described in detail.

30 We shall describe two forms of our invention and shall then point out the novel features therein in the claims.

In the accompanying drawings, Fig. 1 is a diagrammatic view showing one circuit arrangement embodying our invention.

35 Fig. 2 is a diagrammatic view of a second circuit arrangement embodying our invention.

Referring now to Fig. 1, a stretch of railway track made up of the track rails 1 and 2 is divided into track sections 1T and 2T by insulated joints 3. Track section

40 1T is provided with a track circuit including a track battery TB and a track relay 1TR. Relay 1TR controls a slow-release relay TPR which in turn controls a slow-release, slow-pickup relay TZR. Relay TZR controls the gate mechanisms for a pair of traffic gates 4 and 5 which, when in a horizontal position obstruct entrance to the intersection of a highway H and the stretch of railway track. Relay TZR controls another series of cascade connected slow-release relays TZPR, TZPPR and TZZR. Relays 2TR, TZR, TZPR, TZPPR and TZZR jointly control the gate mechanisms for a pair of non-traffic gates 6 and 7 which, when in their horizontal position, obstruct exit from the intersection. Also provided is a crossing relay XR which controls highway crossing signals CS which may be flashing light signals or, as here shown, bells.

55 As here shown, the direction that traffic is to move over the stretch is the direction indicated by the arrow. By the use of additional conventional circuits, the same circuit arrangement can be made to operate for a stretch over which traffic can move in two directions, by substituting a control relay for relay 1TR and having this control relay controlled jointly by track relays associated with the two approach sections to the intersection and associated stick relay, or by the use of an interlocking relay in accordance with well known practice.

As shown in Fig. 1, the apparatus appears in its normal condition. Track relay 1TR is energized by the track battery over the track circuit and its contacts are therefore picked up. Accordingly, relay TPR will be picked up by a circuit which may be traced from the positive terminal B of a battery LB, over front contact

a of relay 1TR, and the winding of relay TPR to the negative terminal N of battery LB. With relay TPR picked up, relay TZR will be energized and its contacts picked up by a circuit which may be traced from positive terminal B of battery LB, over front contact *a* of relay TPR and the winding of relay TZR to negative terminal N of battery LB. Accordingly, the gate mechanisms for gates 4 and 5 will be energized by a circuit which may be traced from positive terminal B of the battery LB, over front contact *a* of relay TZR, and the gate mechanisms 4 and 5, in multiple, to negative terminal N of battery LB. The gate mechanisms may be of any suitable type. For instance, they may be similar to that shown and described in Letters Patent of the United States No. 1,138,087, granted on May 4, 1915, to John P. Coleman for Railway Signals. In the gate application, the gate arm is an extended form of the semaphore of the patent. With the gate mechanisms for the gates 4 and 5 so energized, gates 4 and 5 will be held in a vertical position and highway traffic will be able to enter the intersection.

With relay TZR picked up, relay TZPR will be picked up by a circuit which may be traced from positive terminal B of battery LB, over front contact *b* of relay TZR, and the winding of relay TZPR to negative terminal N of battery LB. With relay TZPR picked up, relay TZPPR will be energized by a circuit which may be traced from positive terminal B of battery LB, over front contact *a* of relay TZPR, and the winding of relay TZPPR to negative terminal N of battery LB. Accordingly, relay TZZR will be energized by a circuit which may be traced from positive terminal B of battery LB, over front contact *a* of relay TZPPR and front contact *c* of relay TZR and front contact *b* of relay 1TR, all in multiple, and the winding of relay TZZR to negative terminal N of battery LB. With the circuit arrangement as shown, the gate mechanisms for non-traffic gates 6 and 7 will be energized and the gates will be held in their vertical position due to energization by a circuit which may be traced from positive terminal B of battery LB, over front contact *a* of relay TZZR and front contact *b* of relay TZPR and front contact *d* of relay TZR and front contact *c* of relay 1TR, all in multiple, and gate mechanisms for gates 6 and 7 in multiple, to negative terminal N of battery LB. Control relay XR will be energized by a circuit which may be traced from positive terminal B of battery LB, over front contact *d* of relay 1TR, front contact *c* of relay TZPPR, front contact *b* of relay TZZR, and the winding of relay XR to negative terminal N of battery LB. Accordingly, the crossing signals CS will be deenergized because their obvious energizing circuits will be open at back contact *a* of relay XR.

Having thus described the circuit arrangement shown in Fig. 1 in its normal condition, let it be assumed that a train enters section 1T from the left and traveling in the direction indicated by the arrow.

As the train enters section 1T, the wheels and axles of the train will shunt relay 1TR causing it to release. When relay 1TR releases the energizing circuit for control relay XR will become open at front contact *d* of relay 1TR and control relay XR will release. Accordingly, the crossing signals CS will commence operating. When relay 1TR releases, the energizing circuit for relay TPR will become open and a snubbing circuit for relay TPR which includes back contact *a* of relay 1TR will become closed. This snubbing circuit prolongs the release time of slow release relay TPR. After the expiration of a period of time, relay TPR will release and open the energizing circuit for relay TZR and close a snubbing circuit for relay TZR including back contact *a* of relay TPR. Relay TZR will not immediately release because of its slow release characteristic but, upon relay TZR releasing, the energizing circuit for the gate

mechanisms of traffic gates 4 and 5 will become open at front contact *a* of relay TZR and gates 4 and 5 will commence moving by gravity to the horizontal or obstructing positions.

When relay TZR releases, the energizing circuit for relay TZPR will become open and a snubbing circuit for relay TZPR including back contact *b* of relay TZR will become closed. Because of the slow release characteristic of relay TZPR, its contacts will not immediately release upon deenergization but will remain picked up for a predetermined period of time. Upon the release of relay TZPR, the energizing circuit for relay TZPPR will become open and a snubbing circuit will be established for relay TZPPR including back contact *a* of relay TZPR. However, the contacts of relay TZPPR will not immediately release due to its slow release characteristic.

With relays 1TR and TZR released, two branches of the energizing circuit for relay TZZR will be open, that is the branch including front contact *b* of relay 1TR and the branch including front contact *c* of relay TZR. Upon the release of the armature of relay TZPR, the third branch of the energizing circuit of relay TZZR will become open and relay TZZR will become deenergized. The contacts of relay TZZR will not immediately release due to the slow release characteristic of relay TZZR. However, when they do release, all the branches of the energizing circuit for the gate mechanisms of non-traffic gates 6 and 7 will be open and gates 6 and 7 will commence to move to their obstructing positions. It should be obvious that the traffic gates 4 and 5 will commence lowering before the non-traffic gates 6 and 7 start moving to their horizontal position. Therefore, any traffic which has already entered the intersection prior to the lowering of the traffic gates will be able to move through the intersection and out again to the highway without being obstructed by the non-traffic gates. It is also clear that with the crossing signals CS in operation prior to the lowering of the traffic gates 4 and 5, traffic will be adequately warned of the approaching train and no traffic will be trapped on the intersection by the time the non-traffic gates are lowered to bar exit from the intersection.

Upon the train vacating section 1T and entering section 2T, track relay 1TR will pick up, and thereby reenergize the gate mechanisms for the non-traffic gates 6 and 7 over a branch of their energizing circuit which may be traced from positive terminal B of battery LB, over front contact *c* of relay 1TR and the gate mechanisms of gates 6 and 7 in multiple, to negative terminal N of battery LB. Accordingly, gates 6 and 7 will commence moving toward their vertical or non-obstructing positions. Relay TZZR will also pick up upon the picking up of relay 1TR due to its energization by a circuit which may be traced from positive terminal B of battery LB, over front contact *b* of relay 1TR, and the winding of relay TZZR to negative terminal N of battery LB. At the same time the energizing circuit for relay TPR will become reestablished and that relay will pick up. When relay TPR picks up, the energizing circuit for relay TZR will be reestablished and after a time delay due to the slow pick up characteristic of relay TZR, it will pick up its contacts and reenergize the gate mechanisms for traffic gates 4 and 5 which will commence moving to their vertical positions. When relay TZR does pick up the energizing circuit for relay TZPR will be reestablished. Therefore, relay TZPR will pick up and reenergize the winding of relay TZPPR which will also pick up. Upon relay TZPPR picking up, the energizing circuit for relay XR will become reestablished and the crossing signals CS will become deenergized. In this manner the circuit arrangement will be restored to its normal condition.

It should be noted that upon relay 1TR picking up, the non-traffic gates 6 and 7 will commence moving to their vertical positions whereas the traffic gates 4 and 5 will not commence moving to their vertical positions until

after a time delay afforded by the slow pickup characteristic of relay TZR. In this way when the entrance to the intersection is cleared by the picking up of the traffic gates, the non-traffic gates will already be in their vertical positions and traffic may move freely over the intersection. Of course, it can be provided that the traffic gates will commence moving to their vertical position simultaneously with the non-traffic gates by using a slow release ordinary pick up relay as relay TZR. However, the staggered raising of the gates is desirable because it eliminates the necessity of battery LB supplying starting current for all the gate mechanisms simultaneously.

Another feature upon the train clearing the crossing section 1T is that the crossing signals CS will continue to operate until after both sets of gates have commenced rising, so as to give a continuous safe indication of a train's presence throughout the train movement. This result is achieved because, in the sequence of events which take place as the circuit arrangement becomes restored to its normal condition, relay TZPPR will be the last relay to pick up and since front contact *c* of relay TZPPR is in the energizing circuit for the control relay XR, control relay XR will not pick up until after the remainder of the circuit arrangement has been restored to its normal position. Therefore, the crossing signals CS will not cease to operate until after the remainder of the circuit arrangement has been restored to its normal position.

Assuming now that after the train clears the intersection and all the gates have commenced moving to their vertical position, a second train enters section 1T. Relay 1TR will release, thereby deenergizing relay XR. Accordingly, the crossing signals CS will immediately re-commence operating. However, the gates will continue moving toward their vertical positions until the relays sequentially release as has already been described and, therefore, the traffic gates will release prior to the non-traffic gates.

However, if the second train enters the section when only the non-traffic gates are rising, the release of relay 1TR will immediately open the only energizing circuit then closed for relay TZZR and relay TZZR will immediately release and deenergize the gate mechanisms for the non-traffic gates 6 and 7 which, accordingly, will immediately reverse their direction and commence moving to their horizontal positions. The traffic gates 4 and 5, under these conditions, will not move from their horizontal position.

In either case it will be apparent that traffic cannot be trapped on the intersection when both sets of gates finally return to their obstructing position.

The circuit arrangement as shown in Fig. 1 is provided with several desirable safety features to provide against failure of several elements in the circuit arrangement. In case the energizing circuit for relay TZPR becomes open for any reason and thereby causes relay TZPR to release, relay TZPPR will also release, as explained in the normal operation of the circuit. However, relay TZZR will not release due to the fact that relay 1TR and relay TZR will still be picked up and, therefore, two of the branches of the energizing circuit for relay TZZR will remain closed. Accordingly, when the track relay 1TR releases, relay TZZR will be unable to release until after relay TZR releases. Therefore, non-traffic gates 6 and 7 will not commence moving to their horizontal position until after the traffic gates 4 and 5 commence moving to their horizontal position. Furthermore, if a wire in the energizing circuit of relay TZPPR becomes broken, relay TZPPR will release but relay TZZR will remain picked up due to the fact that two branches of its energizing circuit will still remain closed and, therefore, non-traffic gates 6 and 7 will not commence to move to their horizontal positions until after relays 1TR, TZR and TZPR release. In the event that the energizing circuit for relay TZZR becomes open the non-traffic gates 6 and 7 will not commence to move to their horizontal

positions until after relay TZPPR releases. In the event that the energizing circuits for relays TZPR, TZPPR and TZZR were all to become open, the non-traffic gates will commence moving to their horizontal position upon the release of relay TZR which will be simultaneous with the traffic gates moving to their horizontal position. In any of these above instances relay XR will become deenergized and the crossing signals will operate. But as already shown, the crossing gates will remain in their vertical positions. Therefore, maintainers will be given a positive warning that something is wrong with the circuit arrangement.

Referring now to Fig. 2, a second embodiment of our invention is shown. In this second embodiment, relays TZPR, TZPPR and TZZR, as shown in the first embodiment, are replaced by a single capacitor snubbed relay TZZR which will have a release time substantially equal to the release time of the series of cascade connected relays TZPR, TZPPR and TZZR, as shown in Fig. 1. The energizing circuit for relay TZZR and capacitor C is obvious from an inspection of Fig. 2 and includes front contact *b* of relay 1TR in multiple with front contact *b* of relay TZR. When this energizing circuit becomes open, capacitor C will discharge through the winding of relay TZZR and that relay will remain picked up until capacitor C has discharged sufficiently to cause it to release.

In operation, when a train traveling from left to right enters the section 1T, the wheels and axles of the train will shunt the track relay 1TR causing it to release and open the energizing circuit for the relay TPR and close a snubbing circuit for relay TPR including back contact *a* of relay 1TR. Due to the slow release characteristic of relay TPR, it will not immediately release but when it does release it will open one branch of the energizing circuit for non-traffic gates 6 and 7. Furthermore, upon relay TPR releasing, it will open the energizing circuit for relay TZR and close a snubbing circuit for relay TZR including a back contact *a* of relay TPR. After a time delay due to the slow release characteristic of relay TZR, it will release and open the energizing circuit for the gate mechanisms of the traffic gates 4 and 5 and, accordingly, the traffic gates will commence moving to their horizontal position. Also, upon the release of relay TZR the energizing circuit for slow release relay TZZR will open, but due to the presence of capacitor C across the winding of relay TZZR, relay TZZR will not release immediately. Not until capacitor C has discharged sufficiently through the winding of relay TZZR so that the voltage across capacitor C becomes equal to the release voltage of relay TZZR will relay TZZR release. Upon its release, all the branches of the energizing circuit for the gate mechanisms of the non-traffic gates 6 and 7 will be open and the non-traffic gates will commence moving to their horizontal position. In a manner similar to that described with reference to Fig. 1, control relay XR in Fig. 2 will release upon the release of track relay 1TR and crossing signals CS will be operating from the time the track relay 1TR releases until, as will presently be shown, relay TZR picks up.

Upon the train vacating section 1T, the track relay 1TR will pick up but relay XR will continue to be released due to the fact that its energizing circuit will be opened at front contact *b* of relay TZZR and front contact *d* of relay TZR. Accordingly, the crossing signals CS will continue to operate. With relay 1TR picked up, relay TPR will once more become energized and will pick up thereby closing the branch of the energizing circuit for non-traffic gates 6 and 7 including front contact *b* of relay TPR. Relay TZZR will once more become energized by a circuit which may be traced from the positive terminal B of the battery LB, over front contact *b* of track relay 1TR, and the winding of relay TZZR to the negative terminal N of battery LB. Accordingly, relay TZZR will pick up and thereby reestablish another of the branches of the energizing circuit for the non-traffic

gates 6 and 7. The non-traffic gates will commence moving to their vertical positions immediately upon the picking up of relay 1TR, since they will be energized in multiple by a circuit including front contact *c* of relay 1TR. The traffic gates will not commence moving to their vertical positions until after relay TZR has picked up and since relay TZR will not pick up until after the time delay afforded by the slow pick up time interval of relay TZR has expired, the traffic gates will not commence moving to their vertical positions until after the non-traffic gates have commenced moving to their vertical positions. Upon the picking up of relay TZR, control relay XR will pick up and crossing signals CS will cease operating and, accordingly, the circuit arrangement will be restored to its original condition.

It should be clear that if a second train enters section 1T while the gates are moving to their non-obstructing positions, no unsafe condition can arise in which traffic will be trapped on the intersection.

In case relay TZZR should become deenergized for some reason, such as one of the leads to the winding becoming opened, relay TZZR will release but the gate mechanisms for the non-traffic gates 6 and 7 will not become deenergized due to the fact that three other branches of the energizing circuit for the non-traffic gate mechanisms will remain closed. These circuit branches include front contact *c* of relay TZR in one branch, front contact *c* of relay 1TR in another branch and front contact *b* of relay TPR in a third branch. Accordingly, if relay TZZR should become inoperative in a release condition, the non-traffic gates will commence moving to their horizontal position at the same time as the traffic gates commence moving to their horizontal position, that is, when relay TZR releases.

As was pointed out earlier, although we have shown our highway crossing apparatus in conjunction with a single direction track, by routine application of a combination of track relays for track sections 1T and 2T in conjunction with associated stick relays, the circuit arrangement can be made to operate for two-direction running. It should also be clear that our invention is not restricted to conventional direct current neutral track circuits but will operate just as well with polar, alternating current or coded track circuits.

Although we have herein shown and described only two forms of apparatus embodying our invention, it is to be understood that various changes and modifications may be made therein within the scope of the appended claims without departing from the spirit and scope of our invention.

Having thus described our invention, what we claim is:

1. In combination with a railway track section intersected by a highway, said track section being provided with a track circuit including a track relay, said intersection being provided with a first set of crossing gates guarding the approach to the intersection and a second set of crossing gates for guarding the exits from said intersection; apparatus for controlling said crossing gates comprising a first series of cascade connected relays including a first relay having a slow-release characteristic and a last relay having a slow-release, slow-pickup characteristic; circuit means for energizing said first relay of said first series closed when the track relay is energized, circuit means for energizing said last relay of said first series closed when said track relay is energized, circuit means for energizing the gate mechanisms of said first set of crossing gates closed when said last relay of said first series is picked up, a second series of cascade connected relays having slow-release characteristics, circuit means for energizing the first relay of said second series closed when said last relay of said first series is picked up, circuit means for energizing the last relay of said second series controlled jointly by the track relay and said last relay of said first series of relays, and circuit means for energizing the gate mechanisms of said second set of

crossing gates controlled jointly by said second series of relays, said last relay of said first series and the track relay.

2. In combination with a railway track section intersected by a highway, said track section being provided with a track circuit including a track relay, said intersection being provided with a first set of crossing gates guarding the approach to the intersection and a second set of crossing gates for guarding the exits from said intersection, a highway crossing signal adjacent said intersection; a first series of cascade connected relays including a first relay having a slow-release characteristic and a last relay having a slow-release, slow-pickup characteristic; circuit means for energizing said first relay of said first series closed when said track relay is energized, circuit means for energizing the gate mechanisms of said first set of crossing gates closed when said last relay of said first series is picked up, a second series of cascade connected relays having slow-release characteristics, circuit means for energizing the first relay of said second series closed when said last relay of said first series is picked up, circuit means for energizing the last relay of said second series controlled jointly by said track relay and said last relay of said first series of relays, circuit means for energizing the gate mechanisms of said second set of crossing gates controlled jointly by said second series of relays, said last relay of said first series and said track relay, and circuit means for controlling the highway crossing signal closed when said track relay is energized and the next to the last relay of said second series of relays is picked up.

3. In combination with a railway track section intersected by a highway, said track section being provided with a track circuit including a track relay, a first set of crossing gates for guarding the approaches to said intersection, a second set of crossing gates for guarding the exits from said intersection, a highway crossing signal adjacent said intersection; a first series of cascade connected relays including a first relay having a slow-release characteristic and a last relay having a slow-release, slow-pickup characteristic; a circuit for energizing said first relay of said first series closed when said track relay is energized, a circuit for energizing the gate mechanisms of said first set of gates in multiple closed when the last relay of said first series is picked up, a second series of cascade connected relays having slow-release characteristics, a circuit for energizing the first relay of said second series closed when said last relay of said first series is picked up, a circuit for energizing the last relay of said second series closed when said track relay is energized, another circuit for energizing said last relay of said second series closed when said last relay of said first series is picked up, a circuit for energizing in multiple the gate mechanisms for said second set of gates comprising a plurality of multiple branches, one of said branches being closed when said track relay is energized, another of said branches being closed when said last relay of said first series is picked up, and a branch being closed when each relay of said second series is picked up, and a circuit for energizing said highway crossing signal closed when said track relay is energized, said last relay of said first series is picked up and the next to last relay of said second series is picked up.

4. In combination with a railway track section intersected by a highway, said track circuit being provided with a track circuit including a track relay, a first set of crossing gates for guarding the approaches to said intersection, a second set of crossing gates for guarding the exits from said intersection, a highway crossing signal adjacent said intersection; a first series of cascade connected relays including a first relay having a slow-release characteristic and a last relay having a slow-release, slow-pickup characteristic; a circuit for energizing said first relay of said first series including a front contact of said track relay, a circuit for energizing in multiple

the mechanisms of said first set of gates including a front contact of the last relay of said first series, a second series of cascade connected relays having a slow-release characteristic, a circuit for energizing the first relay of said second series including a front contact of said last relay of said first series, a circuit for energizing the last relay of said second series including a front contact of said track relay, another circuit for energizing the last relay of said second series including a front contact of said last relay of said first series, a circuit for energizing in multiple the gate mechanisms of said second set of crossing gates comprising a plurality of multiple branches, one of said branches including a front contact of said track relay, a second of said branches including a front contact of said last relay of said first series, and other of said branches each including a front contact of one of the relays from said second series, a control relay, a circuit for energizing said control relay including a front contact of said track relay and a front contact of said last relay of said first series and a front contact of the last relay of said second series, and a circuit for energizing said highway crossing signal including a back contact of said control relay.

5. In combination with a railway track section intersected by a highway, said track section being provided with a track circuit including a track relay, said intersection being provided with a first set of crossing gates for guarding the entrances to said intersection, said intersection further being provided with a second set of crossing gates for guarding the exits from said intersection; a series of cascade connected relays including a first relay having a slow-release characteristic and a last relay having a slow-release, slow-pickup characteristic; circuit means for energizing said first relay of said series when said track relay is energized, circuit means for energizing the mechanisms of said first set of gates closed when said last relay of said series is picked up, another relay, a capacitor across the winding of said other relay to provide it with a slow-release characteristic, a first circuit means for energizing said other relay closed when said track relay is energized, a second circuit means for energizing said other relay closed when said last relay of said series of relays is picked up, and circuit means for energizing said gate mechanisms of said second set of gates controlled jointly by said track relay and said other relay.

6. In combination with a railway track section intersected by a highway, said track section being provided with a track circuit including a track relay, a first set of crossing gates for guarding the entrances to said intersection, a second set of crossing gates for guarding the exits from the intersection, a highway crossing signal adjacent said intersection; a series of cascade connected relays including a first relay having a slow-release characteristic and a last relay having a slow-release, slow-pickup characteristic; a circuit for energizing said first relay of said series including a front contact of said track relay, a circuit for energizing the mechanisms of said first set of crossing gates including a front contact of said last relay of said series, another relay, a capacitor connected across the winding of said other relay to provide it with a slow-release characteristic, a first circuit for energizing said other relay including a front contact of said track relay, a second circuit for energizing said other relay including a front contact of said last relay of said series, a first circuit for energizing the mechanisms of said second set of gates in multiple including a front contact of said other relay, a second circuit for energizing in multiple the mechanisms of said second set of gates including a front contact of said last relay of said series of relays, a third circuit for energizing the mechanisms of said second set of gates in multiple including a front contact of said track relay, a control relay, a fourth circuit for energizing the mechanisms of said second set

of gates in multiple including a front contact of the first relay of said series of relays, a circuit for energizing said control relay including a front contact of said track relay and a front contact of said last relay of said series of relays and a front contact of said other relay, and a circuit for energizing said highway crossing signal including a back contact of said control relay.

7. In combination with a railway track section intersected by a highway; said intersection being provided with a first set of crossing gates guarding the approach to the intersection, a second set of crossing gates guarding the exits of said intersection, and signals for indicating to those on the highway the approach of a train on said railway track section; a control for said signal, means for actuating said control to start operation of said signals in response to the presence of a train in said railway track section, means for causing the first set of crossing gates to move toward a traffic obstructing position at an interval after said signals begin to operate, means for causing the second set of crossing gates to move toward a traffic obstructing position at an interval after said traffic gates have begun to move, means for causing the second set of crossing gates to move out of traffic obstructing position in response to a train moving out of said railway track section, means for causing the first set of crossing gates to move out of traffic obstructing position at an interval after the second set of crossing gates have begun to move out of their traffic obstructing position and means for affecting said control to cause cessation of operation of said signals at an interval after the first set of crossing gates have begun to move out of their traffic obstructing position.

8. In combination with a railway track section intersected by a highway, said track section being provided with a track circuit including a track relay, and said intersection being provided with a first set of crossing gates guarding the approaches to the intersection and a second set of crossing gates guarding the exits from the intersection; a first relay having a slow-release, slow-pickup characteristic; circuit means for energizing said first relay closed when said track relay is energized, a second relay having a slow-release characteristic, first circuit means for energizing said second relay closed when said track relay is energized, second circuit means for energizing said second relay closed when said first relay is energized, circuit means for energizing the gate mechanisms of said first set of crossing gates closed when said first relay is energized; and circuit means for energizing the gate mechanisms of said second set of crossing gates controlled by front contacts of said first relay, said second relay and said track relay in multiple, whereby said first set of gates is lowered before said second set of gates is lowered.

9. In combination with a railway track section intersected by a highway, said track section being provided with a track circuit including a track relay, and said intersection being provided with a first set of crossing gates for guarding the approaches to the intersection and a second set of crossing gates for guarding the exits from said intersection; a series of cascade connected relays including a first relay having a slow-release, slow-pickup characteristic and a second relay having a slow-release characteristic; circuit means for energizing said second relay closed when said track relay is energized, circuit means for energizing said first relay closed when said second relay is energized, a third relay having a slow-release characteristic, first circuit means for energizing said third relay closed when said track relay is energized, second circuit means for energizing said third relay closed when said first relay is energized, circuit means for energizing the gate mechanisms of said first set of crossing gates closed when said first relay is energized; and circuit means for energizing the gate mechanisms of said second set of crossing gates controlled by front contacts of said first relay, said third relay and

said track relay in multiple, whereby the first set of gates is lowered before the second set of gates is lowered.
